UNITED STATES PATENT OFFICE

161,587

FABRIC

Ralph M. Loeff, Chicago, Ill.

Application October 24, 1949, Serial No. 5,677

Term of patent 3½ years

(Cl. D92—1)

To all whom it may concern:

Be it known that I, Ralph M. Loeff, a citizen of the United States, residing at Chicago, in the county of Cook and State of Illinois, have invented a new, original, and ornamental Design for a Fabric, of which the following is a specification, reference being had to the accompanying drawing, forming part thereof.

The figure is a plan view of a fabric, showing my new design.

The design unit is outlined by broken lines. Said unit is repeated over the fabric as indicated.

I claim:

The ornamental design for a fabric, as shown and described.

RALPH M. LOEFF.
